UNITED STATES PATENT OFFICE.

FRANK STARIN, OF SPRINGFIELD, MASSACHUSETTS.

DESIGN FOR A COMBINATION ASH TRAY AND CIGAR CUTTER.

Application filed February 12, 1921. Serial No. 444,608. Term of patent 14 years.

To all whom it may concern:

Be it known that FRANK STARIN, a citizen of the United States, residing at Springfield, in the county of Hampden and State of Massachusetts, has invented a certain new and ornamental Design for a Combination Ash Tray and Cigar Cutter, of which the following is a specification, reference being had to the accompanying drawing.

In the drawing which illustrates this new design,

The figure is a view in perspective, of a combination ash-tray and cigar cutter.

I claim:—

The ornamental design of a combination ash-tray and cigar-cutter, as shown.

In testimony whereof I hereunto affix my signature in the presence of two witnesses.

FRANK STARIN.

Witnesses:

A. P. CONNOR,
THOMAS H. STAPLETON.
